(57) **CLAIM**

The ornamental design for a control device having illumination applied thereto, as shown and described.

DESCRIPTION

FIG. 1 is a front view showing a first state in a sequence of a control device having illumination applied thereto showing our new design;

FIG. 2 is a front view showing a second state thereof;
FIG. 3 is a front view showing a third state thereof;
FIG. 4 is a front view showing a fourth state thereof;
FIG. 5 is a left side view thereof, the right side view being a mirror image thereto; and,
FIG. 6 is a top view thereof, the bottom view being a mirror image thereto.

The drawings include shadows and reflections which indicate contour, not surface ornamentation.

The control device having illumination applied thereto sequentially transitions from the first state to the last state in the sequence. The period with which one state transitions to another state forms no part of the claimed design.
